UNITED STATES PATENT OFFICE.

JAMES A. MONT ROSS, OF CASTLETON, ASSIGNOR OF ONE-HALF TO CALVIN C. WOOLWORTH, OF ALBANY, NEW YORK.

AUTOMATIC REGULATOR FOR PAPER-FEEDING MECHANISMS.

SPECIFICATION forming part of Letters Patent No. 415,877, dated November 26, 1889.

Application filed June 29, 1889. Serial No. 316,011. (No model.)

To all whom it may concern:

Be it known that I, JAMES A. MONT ROSS, of Castleton, in the county of Rensselaer and State of New York, have invented a new and 5 useful Automatic Regulator for Paper-Feeding Mechanisms, of which the following is a specification.

My invention relates to a mechanism for automatically regulating the height of a pile 10 of blanks or sheets of paper or other material to a level required for the proper operation of the feeding mechanism; and it consists of combining with a ratchet-wheel and vibratile arm provided with a pawl fitted to engage 15 with the teeth of said wheel, an electrically-actuated guard which will prevent said pawl from engaging with said wheel when the pile of blanks has attained its proper level.

The object of my invention is to provide a 20 simple and effective mechanism for preventing a pile of blanks from attaining a height at which a feeding mechanism will not perform its work in an efficient manner, and which, when the level of the pile has reached 25 a proper point below the maximum, will automatically start the elevating mechanism in motion. This object I attain by the means illustrated in the accompanying drawings, which are herein referred to, and form part 30 of this specification, and in which—

Figure 1 is a side elevation of my invention, showing the guard in position to allow the pawl to engage with the teeth of the ratchet-wheel. Fig. 2 is a like elevation showing the guard in position to prevent an engagement of said pawl with the teeth of the ratchet-wheel. Fig. 3 is a front elevation of 35 Fig. 1; and Fig. 4 is a detached side elevation showing the opposite side from the one 40 shown in Fig. 1 of the ratchet-wheel, vibratile arm and pawl, and guard.

As represented in the drawings, A designates an intermittently-rotating shaft that is fitted to revolve in the journal-boxes B. Said 45 shaft has a ratchet-wheel C and the bevel-gears D secured to it, and a vibratile arm E loosely fitted thereon by the side of said ratchet-wheel, so that said arm will be left free to swing freely on the shaft without im- 50 parting motion to the latter, excepting as hereinafter explained. At the outer end of the

arm E a pawl F is loosely pivoted thereto, so as to engage in the teeth of the ratchet-wheel C when the guard for preventing an engagement of said pawl with the teeth of the ratchet-wheel is moved into position to permit such engagement. The pawl F is pivoted to the arm E by a pin G, to which one end of a connecting-rod H is attached, the opposite end of said rod being connected to a wrist-pin of 60 a crank I, which is secured to a constantly-revolving shaft J, which is preferably driven by the machine to which the feeding mechanism is applied. The crank I will impart a vibratory motion to the arm E, as indicated 65 by dotted lines in Fig. 1, and said arm will impart an intermittent step-by-step rotative motion to the shaft A whenever the pawl F is permitted to engage with the teeth of the ratchet-wheel C.

The bevel-gears D mesh into corresponding bevel-gears K, which are secured to the feed-screws L, which are journaled in boxes M and have their upper end steadied in openings formed in the top N of the frame of the 75 machine. Said feed-screws are fitted to engage in screw-nuts O on the plate P of the blank-elevating device. Preferably said plate is provided with an auxiliary plate Q, which is supported thereon by springs R, which form 80 an elastic bed for the plate Q, on which the pile of blanks is carried.

S is a guard-lever that is pivoted, as at 1, and arranged at the side of the ratchet-wheel C, so that when the curved portion of said 85 guard-lever is thrown upwardly, as shown in Fig. 2, a pin 2 in the pawl F will ride on said guard-lever and prevent the pawl from engaging with the teeth of said ratchet-wheel, and thereby the rotative movements of said 90 ratchet-wheel are interrupted until the curved portion of the guard-lever is depressed by gravity or other means into position shown in Fig. 1, wherein the pawl F will be free to again engage with the teeth of the ratchet-wheel. The pendent arm of the guard-lever S is connected to a swinging arm T by a rod U, so that said arm and the guard-lever will move synchronously in either direction. The swinging arm T is provided with an armature V, which is arranged in position to be 95 attracted by an electro-magnet W, having 100

one of its wires connected with a battery X and the other wire connected with the free end of a lever Y, whose opposite end is fitted to bear upon a pile of blanks placed on the blank-elevating mechanism. The fulcrum of said lever should be fixed near the pile of blanks, so that a slight movement at the end which bears upon the pile of blanks will produce a greater movement at the outer end of said lever. A contact-point 3 in the outer end of the lever Y is connected to one of the wires of the electro-magnet W, and a corresponding contact-point 4 is fixed to the bracket Z, and has a wire 5 from the battery X connected to it, so that when the outer end of the lever Y is tilted downward by reason of the opposite end of said lever being raised when the pile of blanks has attained the required level the contact-points 3 and 4 will be carried into contact with each other to complete the electrical circuit.

My invention operates in the following manner: When the level of the pile of blanks is below the required height, as shown in Fig. 1, the outer end of the lever Y will be raised to separate the contact-points 3 and 4, and thereby the circuit through the electro-magnet W will be broken, so that the weight of the curved portion of the guard-lever S will cause the armature V to fall back from its contact with the electro-magnet, and said curved portion of said guard-lever will be depressed to allow the pawl F to engage with the teeth of the ratchet-wheel C. The arm E, which is kept constantly vibrating by the crank I, imparts a step-by-step rotative movement to the shaft A during the time the pawl F engages in the teeth of the ratchet-wheel C, and said shaft imparts a corresponding motion to the feed-screws L, thereby causing the pile of blanks to be raised up until the upper side thereof has attained the required level. When this is accomplished the outer end of the lever Y will be in position to bring the contact-points 3 and 4 into close contact and close the circuit through the electro-magnet W. Thereupon the armature V will be instantly drawn into contact with said magnet, and thereby the curved portion of the guard-lever S will be raised to prevent the pawl F from engaging with the teeth of the ratchet-wheel C, so as to stop the rotations of the feed-screws L until the pile of blanks has been reduced in height sufficiently to permit the inner end of the lever Y to fall and its outer end to rise sufficiently to separate the contact-points 3 and 4 from each other, and thereby break the circuit through the electro-magnet W, so as to restore the device to the condition it was in, as

herein set forth, at the time of beginning the above-described operation of my invention. When the pile of blanks on the feeding mechanism has been exhausted, the feed-screws L should be rotated in a reversed direction by 65 means of a hand-crank (not shown in the drawings) applied to the shaft A, and thereby the blank-elevating device will be lowered to a position to receive a fresh supply of blanks. When preferred, a single feed-screw may be 70 substituted for the pair shown in the drawings; but in such case suitable guides should be provided for the plate P, in order that the latter may be confined to a true line in its movement.

While I have herein shown and described my invention as applied to a paper-feeding mechanism, it is applicable, without further invention, to any mechanism for feeding blanks or sheets of any other material. 75 80

What I claim as my invention, and desire to secure by Letters Patent, is—

1. In a feeding mechanism, the combination of a vertically-moving table for carrying blanks thereon, elevating-screws or equivalent means for raising said table, and an electrically-actuated guard or shield for governing the mechanical connection and disconnection of said table-elevating mechanism, with a vibratile arm by which motion is imparted to said table-elevating mechanism, as and for the purpose herein specified. 85 90

2. In a feeding mechanism, the combination of an intermittently-rotating shaft that is geared to the feeding-screws and is provided with a ratchet-wheel, a vibratile arm provided with a pawl which is fitted to engage with the teeth of said ratchet-wheel, an electrically-actuated guard or shield fitted to prevent said pawl from engaging with the teeth of said ratchet-wheel and connected to a swinging armature, an electro-magnet fitted to coact with said armature, a tilting lever having one end fitted to bear upon the pile of blanks held on the blank-elevating device 105 and its opposite end provided with a contact-point which is connected with one pole of the electro-magnet, and a stationary contact-point which is connected with the opposite pole of said magnet, said contact-points being moved to effect a separation or a junction of said contact-points by the variations in the height of the pile of blanks on the blank-elevating mechanism, as and for the purpose herein specified. 110
